CLAIM

The ornamental design for a bag with tie handles, as shown and described.

DESCRIPTION

FIG. 1 is a front view of a bag with tie handles in a closed, flat orientation with a tie handle and a body of each of first and second sides of the bag being aligned together.

FIG. 2 is a perspective view from a top, right side of the bag in an open orientation with the tie handles and upper sections of the sides spaced apart and with a bow formed within the body on the first side.

FIG. 3 is a perspective view from a top, left side of the bag in an open orientation and without bows formed within the bodies; and,

FIG. 4 is a perspective bottom view of the bag in an open orientation with a bow formed within the bodies of the first and second sides of the bag.

The portions of the bag with tie handles shown in broken lines represents the bag's mesh material that does not form part of the claimed design.
